GAS BURNER

Filed Feb. 23, 1928

Inventor
Gaston B. Killam.

say Fotherstonhaugh & Co

Attorney

UNITED STATES PATENT OFFICE

GASTON BROWN KILLAM, OF GREAT FALLS, MONTANA

GAS BURNER

Application filed February 23, 1928. Serial No. 256,359.

My invention relates to improvements in burners for furnaces or other similar heating devices in which the fuel used is gas, and the objects of my invention are to render the gas used for fuel to be as nearly completely combustible as possible; to regulate the volume of gas consumed at any time; to provide an economical sectional gas burner, each section having its own independent source of gas supply, and each section being supplied with adjustable gas outlets capable of being adjusted to be utilized for any size or shape of fire pot; to provide a means for supplying a whirling body of flame within the area of gas combustion so as to distribute evenly and to detain the burning gas therein as long as possible and to render the burner simple in construction with the several parts readily accessible for inspection or repair, and generally to adapt the device better to perform the functions required of it.

I attain these objects by the mechanism illustrated in the accompanying drawings, in which:—

25 Figure 1 is a perspective view of the improved burner with some of the gas outlets omitted, and,

Figure 2 is a cross sectional view through a section of the burner and one of the gas outlets.

Proceeding now to a detailed discussion of the drawings 4 and 5 designate concentric burner sections which may be conveniently formed of suitable piping bent into oval, circular or other desired shape. Each burner section is closed at one end by a plug 6 and is connected at the other end through an elbow 7 to a gas supply pipe 8 equipped with a control valve 9. Through the agency of valves 9 each section of the burner may be turned on or off or otherwise regulated independently of the other section.

Each of the burner sections is further provided with a plurality of openings 10 in which are threaded or otherwise secured the lower ends of a plurality of outlet elbows 11. The upper ends of elbows 11 are externally threaded to receive thereon the nozzles 12. Each nozzle 12 is equipped with a multiplicity of air inlet passages 13 through which

primary air is admitted into the bore of the nozzle to mix with the gas supplied to the nozzle through the elbow 11. The nozzle thus serves as a primary mixing chamber in which the gas is initially mixed with a certain amount of air.

Slidably mounted on each nozzle 12 is a sleeve 14 open at both ends and equipped with a set screw 15 by means of which said sleeve may be secured in adjusted position. Each nozzle 12 is further provided with a plurality of projecting lugs 16 arranged to maintain the inner surfaces of the sleeve and nozzle in spaced relation so as to provide an intervening air passage. The upper portion of the sleeve thus serves as an auxiliary mixing chamber in which additional air is supplied to the gaseous mixture emanating from the nozzle 12 before the mixture reaches the point of combustion which is represented by the upper end of the sleeve. When the sleeve is adjusted downwardly on the nozzle to bring the lower end of the sleeve slightly below the point 12a of the nozzle it will be apparent that the air supplied through the sleeve will be eliminated so that prior to combustion the gas admitted through the elbow 11 is mixed only with the primary air that is admitted into the bore of the nozzle through the openings 13.

Before the burner is installed each gas outlet is properly adjusted so the mixture of gas and air is properly proportioned to insure the most nearly complete combustion of gas.

The volume of heat from this burner may be regulated either by shutting off one or more sections of the burner, or by reducing the volume of gas through the various sections, by adjusting the stop cocks in the supply pipes leading thereto.

It will thus be seen that in this burner I secure economically a wide range of heating capacity from a very low to a very high degree; a high degree of combustion efficiency through the medium of a proper gas and air mixture; a burner which is quickly and easily adjustable to fit varying sizes and shapes of fire pots, by simply altering the direction of the various gas outlets; a burner in which a whirling flame of great intensity can be pro-

duced within the furnace, which tends to distribute the heat evenly and to prevent it becoming dissipated so quickly.

5 I am aware that, prior to my invention, gas burners have been made with sectional construction and with means for adjustably regulating the primary air supplied to the gas before the point where the combustion takes place is reached.

10 I therefore do not claim such a combination broadly, but what I claim as my invention, and desire to secure by Letters Patent is:—

15 1. A burner comprising a revolvably mounted nozzle inclined with respect to its axis of revolution and formed with inlet openings for the admission of air and gas into the bore of the nozzle, a sleeve slidably mounted on the nozzle, there being an air passage reserved between the inner surfaces of the sleeve and nozzle and means for securing the sleeve to the nozzle with the outer end projecting beyond the tip of the nozzle to provide an auxiliary air and gas mixing chamber to which air is admitted through the passage reserved between the sleeve and the nozzle.

20 2. A burner equipped with a nozzle revolvable about a vertical axis and inclined with respect to said axis, said nozzle being provided with openings for the admission of gas and air into the bore of the nozzle, a sleeve slidably receiving the nozzle therethrough, sleeve engaging lugs carried by the nozzle and arranged to allow air to pass between the inner surfaces of the sleeve and nozzle in a direction to mix with the gaseous mixture emanating from the tip of the nozzle and a set screw carried by the sleeve and engageable with the nozzle to secure the sleeve in various predetermined positions of adjustment.

25 3. A gas burner comprising a plurality of concentric burner sections plugged at one end, separate gas supply pipes connected to the remaining ends of said sections, a control valve in each gas supply pipe, a series of nozzles projecting upwardly from each burner section and mounted to rotate about a vertical axis, each nozzle being inclined with respect to its axis of rotation and being provided with passages placing the inner end of the bore of the nozzle in communication with the atmosphere and with the interior of the burner section carrying said nozzle.

40 4. A gas burner comprising a plurality of sections, an independent gas supply means for each section, a multiplicity of revolvably adjustable inclined gas outlets and means for providing an initial and an auxiliary supply of primary air to be mixed with the gas before the point of ignition of the gas is reached.

45 5. A gas burner comprising a plurality of burner sections, each section having an inde-

pendent source of gas supply, a multiplicity of gas outlets carried by each section, and an initial and an auxiliary source of primary air for the gas mixture associated with each gas outlet for the purpose specified.

50 6. A gas burner equipped with a rotatably mounted gas outlet elbow, a nozzle secured to the elbow to receive the gas therefrom, said nozzle being provided with passages arranged to admit air into the bore of the nozzle to mix with the gas therein, a sleeve slidably mounted on the nozzle on such manner as to reserve an air passage between the inner surfaces of the sleeve and nozzle, said sleeve being adjustable to a position cutting off the passage of air between the sleeve and the nozzle or to a second position forming an air and gas mixing chamber beyond the outer end of the nozzle, the air being admitted to the chamber through the passage reserved between the sleeve and the nozzle.

55 7. A gas burner comprising a nozzle having an opening extending therethrough, one end of the nozzle being adapted to be connected with a source of gas under pressure, a portion of the opening between the delivery end and its connection with the source of gas being of smaller diameter than the opening in the delivery end thereof, the wall of the nozzle having air inlet openings on the delivery side of the opening of smaller diameter, a sleeve connected with the nozzle and projecting beyond the tip thereof, the outside diameter of the delivery end of the nozzle being smaller than the inside diameter of the sleeve whereby an air passage is formed between the two, there being air inlets for admitting air into the space between the sleeve and the nozzle.

60 8. A gas burner comprising, a nozzle having a central opening, one end of which is adapted to be connected with a source of gas under pressure, the opening having a section of smaller diameter than the opening at the delivery end whereby a shoulder is formed, the wall of the nozzle having openings that connect the interior adjacent the shoulder with the surrounding air, a sleeve movably connected with the nozzle, the inside diameter of the sleeve being greater than the outside diameter of the nozzle whereby an air space is formed between the two, there being air passages for connecting the air space with the surrounding air.

65 9. A burner comprising a nozzle formed with inlet openings for the admission of air and gas into the bore of the nozzle, a sleeve slidably mounted on the nozzle, there being an air passage reserved between the inner surfaces of the sleeve and nozzle and means for securing the sleeve to the nozzle with the outer end projecting beyond the tip of the nozzle to provide an auxiliary air and gas mixing chamber to which air is admitted

- through the passage reserved between the sleeve and the nozzle.
10. A gas burner comprising a burner section connected with a source of gas supply, a multiplicity of gas outlets carried by the section and an initial and auxiliary source of primary air for the gas mixture, associated with each gas outlet for the purpose specified.
- 10 11. A burner comprising a nozzle having an open outlet at one end and openings at the other end for the admission of gas and an initial supply of air, which pass through the open outlet end thereof, and a burning nozzle having an open end forward of the open end of the first said nozzle and having its rearwardly extending wall surrounding said first nozzle with means for admitting an auxiliary supply of air thereto, said nozzle and initial and auxiliary air admission means being so proportioned that combustion of the air and gas mixture takes place wholly outside of said burning nozzle under normal operating conditions of the burner.
- 25 12. A burner comprising a nozzle having an open outlet at one end and openings at the other end for the admission of gas and an initial supply of air which pass through the open outlet end thereof, and a burning nozzle having an open end forward of the open end of the first said nozzle and having its rearwardly extending wall surrounding said first nozzle with means for admitting an auxiliary supply of air thereto to the rear of said open end of said first nozzle, said nozzles and initial and auxiliary air admission means being so proportioned that combustion of the air and gas mixture takes place wholly outside of said burning nozzle under normal operating conditions of the burner.

In testimony whereof I hereunto affix my signature.
